[57] CLAIM

The ornamental design for a flow stabilizer attachment for the inlet port of a pump, as shown, and described.

DESCRIPTION

FIG. 1 is a bottom perspective view of a flow stabilizer attachment for the inlet port of a pump, showing our new design;

FIG. 2 is a bottom plan view thereof;

FIG. 3 is a left side elevational view thereof, the right side being a mirror image; and,

FIG. 4 is a front elevational view thereof.

Fig. 1.

Fig. 2.

Fig. 3.

Fig. 4.
